UNITED STATES PATENT OFFICE.

GEORGE WM. SAMPLE, OF YORK, PENNSYLVANIA.

OIL MIXER AND EMULSIFIER.

SPECIFICATION forming part of Letters Patent No. 336,438, dated February 16, 1886.

Application filed December 15, 1885. Serial No. 185,779. (No model.)

To all whom it may concern:

Be it known that I, GEORGE WM. SAMPLE, a citizen of the United States, residing at York, in the county of York and State of Pennsylvania, have invented certain new and useful Improvements in Oil Mixers and Emulsifiers, of which the following is a specification, reference being had therein to the accompanying drawings.

10 The object of this improvement is an application of simple construction and operation for mixing and emulsifying oils and oily substances. These results are attained by the mechanism illustrated in the drawings here-
15 with filed as part hereof, in which the same letters of reference denote the same parts in the different views.

Figure 1 is a vertical sectional representation of an oil mixer and emulsifier embodying 20 the features of my improvement. Fig. 2 is a plan view. Fig. 3 is a transverse sectional representation taken on the line *x x*. Fig. 4 is a sectional detail view.

A is a receiver for oils or oily substances. 25 This receiver is made, preferably, of metal, cylindrical in form, and provided with a perpendicular projection, *a*, having a conical socket, as shown, for a purpose hereinafter set forth. The top of the receiver is provided with a screw-thread for the attachment of a corresponding cover or inclosing cap, B, which forms a close oil-tight joint therewith.

C C are supports for the receiver A, and are preferably made integral with a band or ring, 35 C', which fits the receiver A, as shown in Figs. 1 and 3, and is provided with a suitable number of set-screws, *c c*, which secure the connection of the receiver and the supporting mechanism C C C'.

40 D is a metal shaft, having a cone-shaped lower end corresponding to the socket in the bottom of the receiver, as shown at *a*. The upper part of the shaft D is reduced in size and provided with a beveled shoulder, *b*, which fits closely within the lower part of the cap B and prevents the oily matter from working out on the cap.

D² D² are integral radial extensions or arms of a ring, D', which fits snugly around the shaft 50 D, and is rigidly affixed thereto by set-screws *d²*. The ends of the arms D² are slotted for the reception of perforated agitator-blades D³,

which are adjustably secured within the slotted ends of the arms D² by set-screws *d'*. The perforations in the agitator-blades are for the 55 purpose of facilitating the circulation of the oils and mixture of the oily substances when the machine is put in operation. The blades D³ are beveled or curved at one edge, as fully shown at *d* in Fig. 4, for a purpose hereinafter 60 set forth.

G is a power-shaft, provided with a gear-wheel, F, which meshes with a pinion, E, affixed to the shaft D.

H is a funnel for introducing the oil or oily 65 matter into the receiver. K is a drain-pipe for drawing out of the receiver the oil or oily substances after they have been sufficiently mixed or emulsified. The pipe K is to be provided with a stop-cock or other suitable 70 mechanism for preventing the egress of matter contained in the receiver, except as desired.

By reason of the adjustable connection of the blades D³ with the arms D² the blades may be set out and made to bear against the walls 75 of the receiver A, and the oil thus subjected to a rubbing process, as well as being mixed by thorough agitation and circulation. The curved edges *d* of the blades D³ will facilitate such rubbing process by causing the oily matter 80 to pass between the edges of the blades D³ and the walls of the receiver.

The mechanism is specially intended for and adapted to use in the apothecary business; but it is also applicable to mixing oils generally. 85 In the apothecary business a receiver having a capacity of five to ten gallons will be of sufficient size for all purposes, but may be made of any size and adapted to the use of regular oil mixers and dealers. In small machines the 90 gearing may be dispensed with, and the shaft provided with a crank for operating the mechanism by hand.

In mixing oils or oily substances the matter is put into the receiver and the mechanism 95 put in operation until the desired result is produced. For emulsifying oils, for which purpose it is more especially useful and valuable in the apothecary business, the oil is first put into the receiver, and then a suitable quantity 100 of gum-arabic or other necessary ingredients to be mixed with the oils, after which water, sirup, or any medicine is added, and the contents subjected to a rapid rubbing and agita-

tion by motion of the blades until the contents of the receiver are thoroughly emulsified. It is obvious that this process will produce the desired result more quickly and perfectly than can be done by the old method of the mortar and pestle.

The machine may be made in whole or in part of wood or metal.

Having explained the features of my improvement, what I claim as new, and desire to secure by Letters Patent, is—

In an oil mixer and emulsifier, the combina-

tion of the shaft provided with radial arms bifurcated at their ends, the agitating-blades adjustably secured thereto, as shown, and the receiver, substantially as and for the purpose set forth.

In testimony whereof I affix my signature in presence of two witnesses.

GEORGE WM. SAMPLE.
